[57] ABSTRACT

A curtain in which a curtain body and draw tapes therefor have slits and patterns are punched therein, the suspender is inserted through the above mentioned slits, a weight is fitted to the lower end part of said suspender (6), the curtain is fitted in the upper end part to a winding shaft through tubes idling on said winding shaft, the suspender is fitted in the upper end part to said winding shaft and a winder is connected with said winding shaft.

CURTAIN

BACKGROUND OF THE INVENTION

This invention relates to a curtain wherein proper patterns which are also ventilating ports are formed in a part of the curtain.

There has been no combination of a curtain and hanger in both of which patterns which are also ventilating ports are formed. In the present invention, by patterns which are also ventilating ports, if the patterns in the suspender are made to coincide with the patterns in the curtain favorable as a design of the entire curtain when the curtain is lowered, the patterns will become also ventilating ports.

An embodiment of the present invention shall be explained in the following with reference to the drawings in which:

BRIEF DESCRIPTION OF THE DRAWINGS

FIG. 1 is an elevation of the embodiment;

FIG. 2 is a view taken on line II—II in FIG. 1, the view looking in the direction of the arrows;

FIG. 3 is an enlarged perspective view of a part of the curtain;

FIG. 4 is an enlarged vertically sectioned side view of a part of a draw tape as lowered down to the lowermost end;

FIG. 5 is an enlarged elevation of a part as patterns are made to coincide with each other; and

FIG. 6 is a view taken on line VI—VI in FIG. 5, the view looking in the direction of the arrows.

DETAILED DESCRIPTION OF THE INVENTION

A curtain (1) has horizontally long slits (2) punched at regular intervals in the vertical direction, has proper patterns (3) which are also ventilating ports punched in every other space between two adjacent slits (2) and has a proper number of such vertical rows of patterns provided in the horizontal direction and is fitted in the upper end parts to tubes (5) fitted to idle on a winding shaft (4).

A rectangular draw tape or hanger (6) having patterns (7) corresponding to the above mentioned patterns (3) punched at the same intervals, is fitted at the upper end part thereof to the winding shaft (4), and is inserted through the above mentioned slits (2) alternately from the back surface to the front surface and from the front surface to the back surface of the body (1). The tape (6) a bar-shaped weight (8) fitted to the lower end part thereof. The winding shaft (4) is connected at its respective ends with a winder mechanism (9) and a supporter (10) and has collars (11) fitted closely to both ends sides of each tape (6) and collars (12) fitted closely to both side edges of the curtain

2

body (1) so that the curtain (1) may be smoothly elevated and lowered by the tapes (6).

The winder (9) has a winding string (13) and is so constructed as to rotate the winding shaft (4) and to stop it in any rotating position. The winding string (13) can stop in any position the tapes (6) for suspending the curtain. The supporter (10) is rotatably connected with the winding shaft (4).

The operation of the present invention is as follow: 10 First of all, in order to cause the patterns (3) and (7) coincide with each other to provide a ventilating port, the tape (6) is wound up with the winder (9) until the patterns (3) and (7) coincide with each other.

In order to elevate the curtain, if the tapes (6) are 15 wound up with the winder (9), the weight (8) in the lower end part of said tape (6) will be barred by the slits (2) at the lower end of the curtain body (1) and the curtain body (1) will be elevated together with the tapes (6) (FIG. 2) without being wound up on the 20 winding shaft (4) due to the idling of the tubes (5).

In short, in the present invention, the slits (2) and patterns (3) are punched in a part of body (1), and the patterns (7) which correspond to the patterns (3) are punched in a part of each tape (6), the tapes (6) are inserted through the above mentioned slits (2), and a weight (8) is fitted to the lower end part of each tape (6). The curtain body (1) is fitted by its upper end part to the winding shaft (4) through tubes (5) idling on said winding shaft (4), with the tapes (6) being fitted by the 30 upper end parts to said winding shaft (4) and a winder (9) is connected with said winding shaft (4). Therefore, the patterns in the curtain body and tapes can be caused to coincide with each other so as to be convenient for ventilation. Hence, it is possible to adjust the 35 ventilation and lighting, and an esthetic effect can be developed by applying patterns and colors to said curtain body (1). Moreover, as the curtain body (1) and tapes (6) are combined as a double curtain, a sound-proofing effect can be also developed.

40 What is claimed is:

1. A curtain comprising a sheet-like body having at 45 least two rows of horizontal slits arranged at regular intervals in a vertical direction and an open pattern in every other space between two adjacent slits in each row, a draw tape threaded through the slits of each row, each draw tape having patterns corresponding to the patterns of the body and upper and lower end parts, a winding shaft, tubes mounted on the winding shaft for idling thereon, said body having an upper end, means 50 on said upper end of the body fitting the body on said tubes, means attaching the upper end of each tape to the winding shaft, a weight attached to the lower end of each tape, and a winding mechanism operably connected to the winding shaft to rotate the winding shaft.
